UNITED STATES PATENT OFFICE.

JAMES R. AVERY, OF LOUISVILLE, KENTUCKY.

CAR-COUPING.

SPECIFICATION forming part of Letters Patent No. 367,128, dated July 26, 1887.

Application filed April 1, 1887. Serial No. 233,337. (No model.)

To all whom it may concern:

Be it known that I, JAMES R. AVERY, a citizen of the United States, residing at Louisville, in the county of Jefferson and State of Kentucky, have invented new and useful Improvements in Car-Couplings, of which the following is a specification.

This invention relates to car couplers.

The objects are to uncouple cars readily without danger to the operator, and in such manner that the coupling-pin will be held out of the pin-hole and in a position ready to fall back into the hole and to engage with a coupling-link when cars come together to be coupled; furthermore, to cause automatic coupling of the cars upon their coming together; and, finally, to strengthen the device and protect the buffer or draft action in my system of car-coupling.

20 The invention consists in a novel device whereby these objects are attained, which will be hereinafter more fully described, and particularly specified in the claims.

In the accompanying drawings, forming a part of the specification, like letters of reference indicate corresponding parts.

In the drawings, Figure 1 represents a side elevation of the entire device attached to a car, the car being shown in section. Fig. 2 is a vertical sectional view of the coupler-head detached. Fig. 3 is a horizontal sectional view of the same. Fig. 4 is a detail view showing the draw-bar detached. Fig. 5 is a detail perspective view of the cross-bar detached. Fig. 6 is a perspective view of one of the guards detached. Fig. 7 is a detail view of the connecting-bolt and its key. Fig. 8 is a detail view of an attachment-plate. Fig. 9 is a front elevation of the coupling-pin, levers, and gravity-rest.

40 The coupler-head is represented by the letter A, and is here shown provided with a vertical pin-hole, a, extending through the upper and lower walls of the link-rest cavity for the easy insertion and withdrawal of a coupling-pin, P. The coupler-head is provided with a hollow neck or stem, a', formed integral therewith and extending therefrom, through which neck or stem is an opening or channel, a'', which serves for the insertion of a draw-bar, B. The neck or stem of the coupler-head is also provided with a transverse slot, a'', ex-

tending through the same and connecting with the longitudinal channel a'.

The draw-bar B is formed at one end with a 55 square portion, b, the extreme end having lugs extending transversely therefrom, which lugs are adapted to fit against the rear end of the link-cavity during draft action. The surface of the square portion of the draw-bar has cut 60 therein a transverse slot or groove, b', which, when the draw-bar has been placed in position within the coupler-head, will be in line with the transverse slot a'', through which slot and groove is then placed a flat bolt, E. This bolt 65 fits snugly in the groove in the draw-bar and moves therewith, the slot a'' being of sufficient width to allow limited movement of the bolt, occasioned by backward or forward movement of the coupler-head. During forward or draft 70 action of the coupler-head the bolt is drawn against the rear wall of this slot, while during rearward or buffering action of the same it is forced against its forward wall, the bolt thus limiting the movement of the draw-bar and 75 coupler-head, respectively.

Upon the rear portion of the draw-bar is placed a cross-bar, L, from each side of which extend journals c, having at the inner ends square shoulders c', which shoulders form bearings for the rear ends of guards D, which fit snugly therein; the forward ends of said guards being provided with an elongated slot, each fitting over the outer extending ends of the flat bolt E. The guards are held upon the 80 ends of the flat bolt by means of a key, e, at one end, the opposite end of the bolt being turned down at an angle to its length and overlapping the side of the guard. The journals c upon the cross-bar extend through bearings 85 in attachment-plates G, secured to the draft-timbers upon the under side of the car. These attachment-plates are also grooved, as shown at g', to provide for the introduction of cross-braces, thus affording additional means of 90 strengthening the device in attachment and resisting strain caused by draft and buffer action. The journals c are further used as means for attachment of draft-rods H or equivalents at one end, the opposite ends being secured to 95 the king-bolt transom or other part of the car-frame. Also placed upon the rear portion of the draw-bar are springs S S', interposed, respectively, between the coupler-head A and

cross-bar C, and between said cross-bar and rear end of the draw-bar.

The upper portion of the coupling-pin P is bent downward, being about perpendicular to its lower portion, and when in position for operation extends rearward and passes through a loop or eye in the lower end of a vertical operating-rod, L, by means of which the pin may be withdrawn from the pin-hole of the 10 coupler-head.

The vertical operating-rod L is secured to the end of a car by means of staples l, its upper end extending above the top of the car and being curved to serve the purpose of a handle.

15 The lower end of the rod is bent outward, then downward to form a loop or eye, l', through which the horizontal end of the coupling-pin passes, as previously stated. A horizontal rod, M, is also secured to the end of the car, its 20 outer ends extending beyond the sides of the car, being bent to serve as handles for turning. At or near its center is formed a bend or loop, m, which, when the pin is in position within the coupler-head, rests upon the top portion 25 of the pin and between the same and the lower bent portion of the vertical rod. The horizontal rod is secured upon the car at such point that, while occupying this position, its loop or bend extends obliquely downward, so 30 that when the rod is turned it will raise the vertical rod, and hence the coupling-pin, to proper position for coupling. It is necessary when the pin is raised to this point that it should there be held ready to be released by 35 the force of the coming together of the cars. For this purpose I provide an automatic rest, R, pivoted to the end of the car, and of such length that when the rod and pin have been raised to their full height the rest will fall in 40 place beneath the bend of the vertical rod, resting against the end of the horizontal portion of the coupling-pin. Thus the rest will support the vertical rod, and consequently keep the coupling-pin above the pin-hole, 45 ready to be dropped in place for coupling.

When the coupling-pin and its attendant parts are thus set and a car is brought into contact therewith for the purpose of coupling, the force of the blow causes the coupler-head 50 to be forced rearward, and the coupling-pin is carried back with it, the end of the horizontal portion strikes against the rest and pushes it from beneath the vertical rod, allowing it to fall and the coupling-pin to fall into the pin-hole through the link, and thus automatically couple the cars.

It is obvious that in a device thus constructed, the coupling-pin may be set in position for coupling by a person upon the top or at either 55 side of a car, the force of the cars coming together causing the pin to drop in place automatically and without other aid.

Having thus fully described my invention, what I claim as new, and desire to secure by 60 Letters Patent, is—

1. In a car-coupler, a cross-bar having projections forming trunnions extending from it,

said projections having shoulders for the attachment of guards, substantially as described.

2. In a car-coupling, a cross-bar in combination with guards connecting it with a coupler-head or front end of a draw-bar, substantially as and for the purpose specified. 70

3. In a car-coupler, guards, or equivalents, connecting a cross-bar with a coupler-head or draw-bar, substantially as and for the purpose set forth. 75

4. In a car-coupler, attachment-plates having transverse grooves or recesses in their edges forming bearings for jugs and cross-bars, 80 either or both connecting the draft-timbers or secured thereto by rods to prevent the spreading and splitting of said timbers, substantially as specified.

5. In a car-coupling, the combination of a 85 coupler-head having a transverse slot through its stem, a draw-bar provided with a slot or suitable recess, a cross-bar having projections and slotted lateral guard or guards, a bolt passing through the slots in the guards and through 90 the slot in the draw-head, substantially as and for the purpose set forth.

6. In a car-coupling, the combination of a coupler-head having a transverse slot through its stem, a draw-bar provided with a slot or 95 recess, a cross-bar having projections slotted or otherwise, suitably-constructed guard or guards, a bolt passing through the slots in the guards and coupler-head and engaged by the slot or recess in the draw-bar, a spring placed 100 upon the draw-bar between the coupler-head and cross-bar, and another spring bearing against the rear side of the cross-bar, all combined and arranged to operate in the manner and for the purpose specified. 105

7. In a car-coupler, an angled pin, in combination with a coupler-head and gravity-latch, whereby when withdrawn from the link-cavity one end of the pin remains suspended in the pin-hole of the coupler-head, while the 110 other end extends rearward a sufficient distance to disengage itself by striking and forcing back the device supporting it, substantially as specified.

8. In a car-coupler, the combination, with an 115 angled pin, a vertical rod adapted to be fastened to the end of a car, the upper end of the rod being bent to serve as a handle, its lower end being bent outward and downward to form a shoulder, and its lower end also having a 120 loop formed thereon through which the upper end of the coupling-pin passes, substantially as shown.

9. In a car-coupling, the combination of a 125 coupling-pin having a bent upper portion, a vertical rod bent at its lower end to form a shoulder, and having a loop formed upon its lower bent end, through which the upper portion of the coupling-pin passes, and a horizontal rod having handles formed thereon, and 130 provided with a loop or bend at or near its center for engagement with the bent portion of the vertical rod, whereby movement of the horizontal rod will cause the vertical rod to be

raised, and thus remove the pin from the pin-hole in the draw-head, substantially as shown and described.

10. In a car-coupler, a gravity-rest pivoted 5 to the end of the car, in combination with a bent rod and angled pin, the rest engaging the coupling-pin when withdrawn from the pin-hole, but the outer end of the pin being in close proximity to said rest, so that the force 10 imparted by the coming together of the couplers forces the rest back and releases the pin, substantially as specified.

11. In a car-coupler, the combination, with 15 the coupling-pin, of the vertical rod for raising the coupling-pin out of the pin-hole, a horizontal rod having a loop bearing against the under side of the bent portion of the vertical rod for the purpose of raising the rod and thus withdrawing the pin from the pin-hole, 20 and a rest pivoted upon the car at one end, its opposite end adapted to drop beneath a portion of the vertical rod to support the rod and thus hold the pin out of the pin-hole, substantially as and for the purpose set forth.

25 12. In combination with a car, journal bearing-plates attached thereto, a cross-bar pivoted therein, draft-rods connecting the cross-

bar with the king-bolt transom, and another cross-bar, a draw-bar with a coupler-head secured upon the front end and adapted to slide 30 thereon longitudinally, the stem of said draw-bar supported in a bearing provided through the pivoted cross-bar, a guard upon each end of the cross-bar connecting it with the front end of the draw-bar in the coupler-head by means 35 of a bolt therein, a spring interposed between the coupler-head and cross-bar, and a spring interposed between the cross-bar and a washer or other abutment impinged against a key in the draw-bar near its rear end, all substantially 40 as shown, and for the purpose specified.

13. In combination with a car and coupler, a gravitating rest pivoted to the end of the car, a vertical rod adjusted to engage with said rest, a horizontal rod adjusted to engage with 45 said vertical rod, a coupling-pin angled to engage a link in the cavity of the coupler-head of the coupler with its lower end, and the vertical rod with its upper end, substantially as shown, for the purpose specified.
